UNITED STATES PATENT OFFICE

JOSEPH RABER, OF HADDONFIELD, NEW JERSEY, ASSIGNOR, BY MESNE ASSIGNMENTS, TO RADIO CORPORATION OF AMERICA, OF NEW YORK, N. Y., A CORPORATION OF DELAWARE

PICKUP ARM

Application filed May 22, 1931. Serial No. 539,310.

The present invention relates to electric sound translating apparatus and more particularly to a unitary part thereof which may be termed the sound translating unit.

Such a unit includes the electric sound translating device, or electric pickup, and the suspension means therefore, by which it is mounted in the sound translating apparatus and permitted to move in operating relation to the sound record.

A unit of the above character provides for carrying the electric pickup device at one end of a beam or arm which is pivotally mounted adjacent its opposite end in a suitable swivel pedestal or supporting means and the arm is suitably counterweighted to compensate for the weight of the pickup device and provide the desired pressure of the stylus of the pickup device upon the record or sound track.

Sound translating units of this character known heretofore have assumed various forms and have embodied a variety of mounting means for the supporting arm or beam requiring a relatively large clearance space in the cabinet structure of the apparatus, for proper operation.

It is an object of the present invention to provide an improved electric sound translating unit of the type embodying an electric sound translating device, a suspension arm and a supporting pedestal therefor, which, while permitting full operating movement of the translating device, is of compact construction adapted to operate in a space of greatly reduced dimensions from that heretofore known.

It is a further object of the present invention to provide an electric sound translating unit of the above character, the elements of which are arranged to provide for easier operation and which have an improved operating characteristic.

The invention will, however, be better understood from the following description when taken in connection with the accompanying drawing and its scope will be pointed out in the appended claims.

In the drawing Fig. 1 is a view in perspective on a reduced scale of an electrical sound

translating unit embodying the invention; Fig. 2 is a cross sectional view on the same scale of a portion of the unit shown in Fig. 1, further illustrating the construction thereof; Fig. 3 is a cross sectional view of a portion of the unit shown in Fig. 2 taken on the section line 3—3; Fig. 4 is a cross sectional view of the electric sound translating device or pickup; and Fig. 5 is a side view on substantially the same scale, of a modification of a portion of the unit shown in Figs. 2 and 3.

Referring to Figures 1, 2, 3, and 4 of the drawing, 8 is a sound translating device which is mounted upon an elongated suspension arm 9 in turn supported by a swivel pedestal 10 and provided with a suitable counter weight means 11 for the translating device. The pedestal is mounted in a sound translating apparatus 12 and is arranged to carry the translating device 8 in operating relation to a sound record 13 with which, in Figure 1, the stylus 14 of the sound translating device is shown in operating engagement.

The suspension arm is enlarged or flared at its end opposite the translating device and provided with flanged edges 14 adapted to enclose the upper end of the pedestal 10, and the counter weight means 11. The latter is secured to the arm and is arranged to lie between two spaced parallel ears 15 provided upon the pedestal 10.

The axis of rotation for the pedestal is provided by a central hollow pivot pin 16, and substantially in alignment therewith and at a right angle thereto there is provided a horizontal pivot axis provided by a pivot pin 17 for the suspension arm about which it may be moved to lift the translating device from the record and to return it thereto. This operation is necessary for changing records and for changing the needle of the stylus 14 and is the usual pivot axis employed in known suspension means for sound translating devices of this character.

In the present example, however, and in accordance with the invention, there is provided a second pivot axis or pivot pin 18 parallel with the first and spaced therefrom preferably in advance of the axis 16 and in advance of the axis 17 toward the translating

- device. This axis is provided by a second pivot pin 18. This is covered by a body of vibration absorbing material such as a sleeve or tube 19 of rubber or other suitable resilient material. The pin 18 is carried at its ends and secured to the flanges 14 of the flanged portion of the arm and the sleeve 19 rests adjacent its ends in a saddle in the pedestal provided by parallel notches 20 in the ears 15.
- 10 It will be seen that the arm 9 may be lifted about the axis 17 whereby the pivot axis 18 will be caused to move with the arm about the axis 17. This permits advantage to be taken of the full length of the suspension arm 15 from the pivot axis 17 to the translating device in operation as hereinbefore mentioned. A large portion of the counter weight 11 is carried in advance of the pivot axis 17 and extends a relatively short distance to the rear 20 of said axis. Hence, as indicated in Figure 2, by the raised position of the arm indicated at 21, a very low pedestal may be provided and a very short clearance distance is necessary for the operating movement of the counter weight end of the lever.
- 25 Full operating advantage of the counter weight is obtained, however, by permitting the arm to pivot about the axis 18 when the stylus of the translating device is in engagement with the record 13. This is provided by permitting a slight operating movement of the arm about the pivot axis 18 by the arrangement of the pivot axis 17 as indicated in the drawing. The pivot pin 17 is carried 30 by the flanges 14 of the suspension arm 9 in the same manner as the pin 18. The pin 17 is then journaled in the ears 15 in loose bearings provided by enlarged openings or apertures 22 in the ears, of a diameter sufficient 35 to permit a slight movement of the arms about the pivot axis 18 as the stylus of the translating device follows the irregularities in the movement of the record surface in a vertical direction.
- 40 45 The suspension arm is thus arranged to rotate in a single plane about two separate spaced parallel axes provided by two spaced parallel pivot pins 17 and 18 which in turn are at a right angle to the pivot pin 16 for the pedestal. The pedestal is provided with a loose bearing for the pivot pin 17 and a saddle type of bearing for the pivot pin 18, the latter being provided by extending the pedestal forwardly as indicated more clearly in the 50 cross-sectional view provided by Figure 2. The movement of the arm about the axis 18 is such that when the arm is in the operating position and the stylus is resting upon a record, as shown in Figure 1, the excess weight 55 of the translating device upon the record above that desired for proper stylus pressure is counterbalanced by the weight 11 to the rear of pivot pin 18, and rotation takes place during the record translation about the pivot pin 18. The difference in diameter between

the pin 17 and that of the apertures or openings 22 in the pedestal provides sufficient play to permit the stylus to accommodate itself to any vertical irregularity that may be encountered in the surface of the record. The 70 pivot pin 20 and its resilient sleeve 19 resting in the notches 20 may be freely disengaged from the extension of the pedestal when it is desired to raise the stylus from the record, the arm then moving about the pivot axis 75 provided by the pin 17.

By the construction shown and described, whereby a separate pivot axis is employed for the translating process, the counter weight 11 may thus be located in a more forward position 80 over the pedestal 10 and hence takes up a minimum of space to the rear. This weight is made effective by the change of the pivot axis.

It will be noted that the translating device 85 and arm, including the counter weight, lie in substantially a common horizontal plane passing substantially through the pivot axes 17 and 18. With this arrangement, a sound translating unit of minimum height is obtained and as indicated more clearly in Figure 4 by providing that the axis of rotation 23 of the stylus 14 lies in the extension of the arm 9 and substantially in a common plane therewith, an improved operating characteristic 90 is obtained. This is for the reason that with the axis 23 of the stylus substantially in the plane of the arm, a lesser torsional vibration is imparted to the arm by movement of the stylus.

100 In the present example, the stylus is provided with an armature 24 located in an electrical pickup coil 25 and provided with a suitable field magnet 26 and a cover means 27. The pickup coil 25 is provided with output 105 leads indicated at 28. This represents any suitable electrical or other sound translating device, the general arrangement of which is such that it lies substantially in continuation and in the plane of the suspension arm 9. 110

This construction has the advantage that, as above mentioned, in height or vertical depth, the unit is reduced to a minimum dimension and improved response is provided because of the reduction of torsional vibration 115 from the stylus being translated to the arm.

120 It should be noted that the stylus 14 is arranged to lie at an acute angle with respect to the pivot axis 23. In operation, this arrangement provides for smooth operation of the stylus in the record track and that the pivot axis 23 lies substantially parallel to the record surface.

125 Referring now to the modification shown in Fig. 5, the two axes corresponding respectively with those defined by the pins 17 and 18, in Figs. 1, 2, and 3 are connected by a link member 29, the same comprising parallel side members 30 (one only being shown) connect- 130

ed through extensions 31, by cross member 32. The pedestal 33, on which a suspension arm 9 is pivotally mounted, is provided at its upper end with a yoke 34, having spaced ears 35, (one of which is shown), and the side members 30 are pivotally connected herewith by pivot pins 36, (one of which is shown), and to the arm by a pin 37. The pins 36 define the axis of rotation corresponding to that defined by the pin 17 in Figs. 1, 2, and 3, and the pin 37 defines the axis corresponding to the axis as defined by the pin 18 in said figures. In this construction, the pin 37 is not disengageable from the link or from the arm, 15 the said link being rotatable with the arm, in moving the stylus to and from playing position.

The link 29 is held in a horizontal position during the translation of a record by abutment of the rear edge of the cross member 32 against the yoke 34. There is no connection between the arm 9 and the pedestal on the pivotal axis defined by the pins 36. In consequence, when the arm 45 is in playing position, all rotation will occur around the axis defined by the pin 37.

The moments about the pivotal point, defined by the pin 37 in Fig. 5, are similar to the moments described in connection with Figs. 1, 2, and 3, so that the counterbalance weight required on the side of this axis of rotation opposite to the pickup may be as slight as possible.

It will thus be seen that a sound translating unit has been provided which is adapted to translate sound records with greater fidelity and which to this end provides a sound translating device which lies in the same horizontal plane with the suspension arm to 40 which the device is secured, and that the pivot axis of the stylus or armature of the translating device lies in the same plane of the arm and substantially in continuation of and coaxial with the longitudinal axis of the 45 arm. Furthermore, two parallel pivot axes are provided for the arm, one of which lies in a more forward position toward the translating device with respect to the other, and that these axes lie in the plane of the arm in common with the counter weight means. This 50 arrangement reduces the space required to the rear of the arm for the reason that the counter weight is carried in a more forward position with respect to the main pivot axis.

55 It should be noted that the axis defined by the pin 18 in Figs. 1, 2 and 3 and by the pin 37 in Fig. 5, is located as far forward as practicable toward the translating device, to utilize a greater portion of the mass of the arm 60 as part of the counter weight structure whereby the moment on the side of this axis toward the translating device above that required for faithful tracking of the stylus in a record groove, and the mass of the counter- 65 weight, may be reduced to a minimum. The

added mass required for counterbalancing purposes may thus be materially reduced as compared with commonly known constructions of this character and, in consequence, the projection of the arm rearwardly of the pedestal may be minimized. At the same time, the desired length of the radius of horizontal rotation of the unit about its vertical axis, as is desirable for faithful translation of a record is preserved. 70

75 Although I have shown and described certain specific embodiments of my invention, I am fully aware that many modifications thereof are possible. My invention, therefore, is not to be restricted except insofar as 80 is necessitated by the prior art and by the spirit of the appended claims.

I claim as my invention:

1. In an apparatus of the character described, a sound translating device, an arm for supporting said device, a supporting means for the arm, and means providing spaced parallel axes of rotation between the arm and the support therefor, said arm being rotatable relative to the supporting means 90 selectively about said axes. 85

2. In an apparatus of the character described, a fixed supporting pedestal, a sound translating device, an arm for supporting said device, and means providing spaced parallel axes of rotation for said arm with respect to said pedestal, one of said axes being arranged to rotate about the other. 95

3. In an apparatus of the character described, a fixed supporting pedestal, a sound translating device, an arm for supporting said device, means providing spaced parallel axes of rotation for said arm with respect to said pedestal, one of said axes being arranged to rotate about the other, a movable stylus for said device, and means providing a pivot axis for said stylus substantially in the plane of said arm. 100 105

4. In an apparatus of the character described, the combination of a support, a sound translating device, a suspension arm for said device, and means providing substantially parallel axes of rotation for said arm about said support, said axes being so spaced and related that the arm may be moved about one of said axes during sound translation, and about the other in moving the translating device to or from a sound translating position. 110 115

5. In an apparatus of the character described, the combination of a supporting pedestal, a sound translating device, a suspension arm for said translating device, said arm having a pair of pivot axes about either of which selectively the arm is movable in the same plane, and pivot means for said arm arranged to permit movement of said arm in a plane at a right angle to said first-named plane. 120 125

6. In an apparatus of the character de- 130

- scribed, the combination of a pedestal, a sound translating device, a suspension arm for said translating device, said arm having a pair of pivot axes about which the arm is movable in substantially the same plane, a movable stylus for said device, and means providing a pivot axis for said stylus substantially in the plane of the arm.
7. In combination, a sound translating device, a suspension arm therefor having a longitudinal axis, a support for said arm, means providing a pair of pivot axes for the arm arranged to permit rotational movement of the arm with respect to the support, a stylus for said device, and means providing a pivot axis for said stylus substantially coaxial with the longitudinal axis of said arm.
8. In a device of the character described, an elongated suspension arm, a sound translating device secured to said arm and having a body lying substantially in the plane thereof, said device having a movable armature, and means providing a pivot axis for said armature lying substantially in extension of the longitudinal axis of the arm.
9. In a sound translating apparatus, the combination of a sound translating device, a movable suspension arm to which adjacent one end said device is connected, means providing a horizontal axis of movement for said arm at a point along said arm, in spaced relation to the translating device, and means providing a second horizontal axis of rotation for said arm at a point along said arm between said first-named horizontal axis and said device.
10. In an apparatus of the character described, a sound translating device, a suspension arm therefor, a pedestal for supporting the arm having pivotal movement about an axis for swinging the arm in a horizontal direction, a horizontal pivot means arranged to pivotally connect the arm and the pedestal to permit movement of the arm in a vertical plane, a second pivot means located between the first-named pivot means and said device, said second-named pivot means being movable with respect to the pedestal in a vertical plane about the axis provided by said first-named pivot means.
11. In a device of the character described, a sound translating device, a suspension arm therefor, a pedestal for said arm, means providing a horizontal extension for the pedestal, means providing a pivotal connection between the pedestal and arm defining an axis of rotation for movement of the arm in a vertical plane, and means providing a second axis of rotation for the arm providing for movement of the arm in the same vertical plane, said last-named means being movable with said arm and extension means about the first-named axis.
12. In a phonograph apparatus, a sound translating device, an arm supporting said
- device, means providing a pair of pivotal axes spaced along said arm about which the arm is adapted to have pivotal movement selectively; one of said axes being more remote from the translating device than the other in a direction along said arm.
13. The combination with a sound translating device, of a supporting arm therefor, said arm and device being arranged to lie in a common plane, a supporting means for the arm provided with a pivot axis perpendicular to said plane, means providing a pivot axis between said arm and said support in the plane of the arm and at a right angle to the first-named pivot axis, and means providing a second pivot axis between the arm and the support.
14. A sound translating unit comprising in combination a sound translating device having a stylus adapted to engage a record surface at an angle thereto and a pivot axis for said stylus arranged to lie substantially parallel with a record surface when the stylus is in engagement therewith in operation, a suspension arm for the translating device arranged to lie in a common plane with the axis of said stylus, a support for the arm adapted to be pivotally mounted, and means providing two spaced parallel pivot axes for the arm in connection with said support.
15. A sound translating unit comprising in combination, a sound translating device, a suspension arm therefor to which said device is connected adjacent one end, said arm and said device being arranged to lie substantially in a common plane, a supporting pedestal for the arm connected therewith in spaced relation to the translating device, a pair of spaced parallel pivot axes in said connection about which said arm is movable in the same plane, and means for causing one of said pivot axes to become effective as a pivot axis for the arm when in a playing position and for the other pivot axis to become effective when the arm is in a raised position from the playing position.
16. A sound translating unit comprising in combination, a sound translating device, a suspension arm therefor, a counterweight means for said arm, an operating pivot axis for said arm between said counterweight and said translating device, and means for causing said pivot axis to shift to a predetermined position away from said translating device when said arm is raised from the operating position.
- In testimony whereof, I have hereunto subscribed my name this 19th day of May, 1931.
- JOSEPH RABER.
